UNITED STATES PATENT OFFICE.

WARNER R. BUXTON, OF LONGMEADOW, MASSACHUSETTS, ASSIGNOR TO BUXTON,
INCORPORATED, A CORPORATION OF MASSACHUSETTS.

KEY-CASE HOLDER.

Application filed June 8, 1922. Serial No. 566,869.

To all whom it may concern:

Be it known that I, WARNER R. BUXTON, citizen of the United States, residing at Longmeadow, in the county of Hampden 5 and State of Massachusetts, have invented new and useful Improvements in Key-Case Holders, of which the following is a specification.

This invention relates to improvements in 10 key case holders such as are employed in key cases for the purpose of supporting key retaining members, such as snap hooks, for swinging movement into and out of the case.

The particular key case holders, with 15 which this invention is particularly concerned, are comparatively simple, one piece members which are usually stamped from sheet metal and which have the pivots for the key retaining members incorporated into 20 the holders as integral parts thereof, as distinguished from holders wherein the key retaining members are connected thereto through the intermediary of removable pins or the like. In holders of the present type, 25 of which U. S. Letters Patent No. 1,403,445 granted January 10, 1922, to Daniel E. Reiter, shows one example, the eyes of the key retaining members cannot be entirely closed until the members have been assembled 30 in the holder. Numerous disadvantages follow because of this fact. The key retaining members cannot be completely finished at one operation. They cannot be hardened and properly tempered to the 35 proper degree for, when so treated, the eye cannot later be closed down without breaking or injuring the metal. Consequently, the key retaining members do not generally stand up so well in service as they should 40 because of the insufficient heat treatment. Also the cost of assembly is increased due to the operation of closing down the eyes over the pivots, which operation would otherwise ordinarily be accomplished during 45 the manufacture of the hook without any greater cost for it is practically as expensive to form a partially closed eye as a completely closed one.

This invention is directed to the improvement of that particular class of key holder described to the end of adapting it to receive key retaining members, the eyes of which are completely formed, and of eliminating the disadvantages heretofore thought

to be necessarily incident to holders of the 55 type defined.

Other objects and advantages will appear in the following description and in the illustrative embodiment of the invention in the accompanying drawings, in which,—

Figs. 1 and 2 are small scale front elevational views of a key case embodying the invention showing the case opened and closed respectively;

Fig. 3 is an enlarged fragmentary front 65 elevational view showing in detail one form of the key case holder;

Fig. 4 is a cross-sectional view thereof taken on the line 4—4 of Fig. 3;

Fig. 5 is a view, taken similarly to Fig. 3 70 and showing another form of the key case holder;

Fig. 6 is a cross-sectional view taken on the line 6—6 of Fig. 5;

Figs. 7, 8, and 9 are enlarged fragmentary 75 front elevational views of the type of key holder shown in Fig. 3 and illustrate three different ways of constructing the integral pivot forming devices so as to permit convenient assembly of the key retaining members thereon;

Figs. 10, 11, and 12 are fragmentary top plan views of the structures shown in Figs. 7, 8, and 9 respectively;

Fig. 13 is an enlarged fragmentary sec- 85 tional elevational view illustrating how the pivot forming device shown in Figs. 9 and 12 is applied to a key case holder of the type shown in Fig. 5; and

Fig. 14 is a fragmentary front elevational 90 view of a third form of key case holder.

Referring to these drawings; the key case holder consists of a small sheet metal plate 15, which is preferably so constructed that it can be formed entirely by stamping or 95 punching operations. It is constructed, in a manner later to be described, with a plurality of integral pivot forming devices, upon which are pivotally mounted a plurality of key retaining members 16, of any suitable 100 form. The key case holder is a separate and distinct unit, adapted to be manufactured and sold as such, and is adapted to be permanently secured in any suitable way to the key case proper.

The key case itself may be constructed in any suitable way and that construction illustrated in Figs. 1 and 2 has been found

suitable and is preferred although it is not necessarily essential. The key case, as shown, consists of a single strip of flexible material, such as leather or the like, the end portions 17 of which constitute flaps and are foldable along lines of fold 18 in overlapping relation over the central portion 19, which constitutes the back of the key case. The flaps 17 may be releasably held together 5 by any suitable means, of which the interengageable male and female fasteners 20 and 21, respectively are an example. The holder 15 is preferably secured to back 19 at a location closely adjacent its upper end 10 and the means shown for securing the holder consists of several eyelet rivets 22.

The key case holder 15 is provided with a plurality of slots 23 adjacent its upper edge and the portions 24 on either side of 20 each slot constitute fingers. The pivot forming devices are disposed across the slots 23 and function to pivotally support the key retaining members 16, each of which has a closed, or substantially closed eye 25, 25 for this purpose. The function of the fingers 24 is to maintain the key retaining members in spaced relation on the holder 15 and to restrain them against undue longitudinal movement on the pivot forming 30 devices to be described. To this end the latter are preferably disposed across their slots 23 intermediate the ends of the latter. The fingers may be left flat, or substantially so, as shown in Figs. 3 and 4, or they may 35 be rolled up in hollow and substantially cylindrical form, as shown in Figs. 5 and 6, to form spacing lugs 26, which more effectively perform their intended functions by reason of the increased thickness (preferably substantially commensurate with the outside diameter of eyes 25) afforded by rolling them up.

The pivot forming devices consist of lugs or projections, which are integral with the holder 15 and extend across and substantially bridge the slots 23. Each lug, however, is connected to the holder at one end only so that a free end is left, which may be bent or deflected from its normal position, wherein it is disposed in the same or substantially the same plane as the fingers, to a position out of such plane, whereby the eye 25 may be slipped over the lug and the latter then bent back to its original position.

The result described may be effected in many various ways, a few of which are illustrated in Figs. 7 to 12 inclusive. Thus, as shown in Figs. 7 and 10, the pivot forming device may consist of two lugs 27, each of which is connected at one end to a finger 24 and which extend from opposite side walls of a slot 23 toward each other. The free ends of this pair of lugs may meet one another or there may be a slight space be-

tween them. One of these lugs may be bent outwardly, as shown by dotted lines in Fig. 10, to permit the eye 25 to be slipped over it and then bent back to its original position shown by full lines. This arrangement is 70 suitable where a close restraint of the key retaining members 16 against axial movement is not required for one lug must be at least equal in length to the length of eye 25 measured in the direction of its axis and 75 the length of the other lug represents clearance or the degree of axial freedom of the key retaining member. The advantage of this arrangement is that the break in the pivot forming device is not so readily apparent, being normally covered by the eye 25. One projection only, as shown at 28 in Fig. 8 may be used, in which case the length of the lug may be made more nearly commensurate with the axial length of eye 25, 80 thereby admitting of less side play of the key retaining members 16. The lug may be longer than the width of its slot 23, as shown at 29 in Fig. 8, and its free end may be received in a recess 30 in the opposite 85 side wall of the slot. This particular lug 29 is made of spring metal which may be deflected outwardly within reasonable limits and will spring back to the illustrated and pivot forming position shown. The free 90 end of this lug 29 is preferably turned outwardly slightly to facilitate the entrance of eye 25 thereon.

The various ways described for constructing the pivot forming devices are applicable 100 to either type of holder described, as will be apparent from Fig. 13 in which a spring finger or lug 31, similar to the lug 29 described, is shown as extending from one spacing lug 26 to the opposite lug 26 and as 105 having its free end received in a recess 32 in the opposite spacing lug 26.

It is not necessarily essential that the pivot forming devices extend across the slots intermediate their ends, although this arrangement is generally preferred. Thus, as shown in Fig. 14, a key holder 33 has slots or openings 34 therein closely adjacent its upper edge and the pivot forming device consists of lugs 35 which bridge, or substantially 115 bridge, across these slots at their upper ends.

With the type of holder shown in Figs. 3 and 4, I prefer to offset the pivot forming devices from the body of the holder 15 to leave a space between them and the back 19 of the key case, for the purpose of receiving the back portions of eyes 25 and permitting the key retaining members to swing freely. Also this arrangement prevents the bulging of the flexible back 19 by the eyes 25, which 125 would otherwise occur. This offsetting may be effected in many various ways, as in the patent heretofore alluded to, wherein the devices themselves are bent. I prefer, however, to bend the finger portions 24 of the 130

holder outwardly away from the body of holder 15 and from back 19. One way of bending the fingers is clearly shown in Fig. 4.

With the type of holder shown in Figs. 5 and 6, I prefer to locate the pivot forming device (there indicated by 28) in such a way that when the fingers are rolled up, the device will be properly offset away from back 19 and the particular location shown in Fig. 6 is preferred.

The invention has been disclosed herein for illustrative purposes but the scope of the invention is defined by the appended claims rather than by the foregoing description.

What I claim is:

1. A key case holder, comprising, a sheet metal plate having a plurality of slots therein adjacent one edge thereof, and lugs integrally with the sheet and projecting into the slots to substantially bridge across the latter and support key holders, each of said lugs having one end only attached to the sheet so that its other end may be bent outwardly to permit key holders to be conveniently mounted thereon.

2. A key case holder, comprising, a sheet metal plate having a plurality of slots there-

in adjacent one edge thereof and an integral part connected to and extending from one side wall of the slot across the latter and terminating adjacent but not connected to the opposite wall of the slot.

3. A key case holder, comprising, a sheet metal plate having a plurality of slots therein adjacent one edge thereof and an integral part connected to and extending from one side wall of the slot across the latter intermediate its ends and terminating adjacent but not connected to the opposite wall of the slot.

4. A key case holder, comprising, a sheet metal plate having a plurality of slots therein adjacent one edge thereof and an integral part connected to and extending from one side wall of the slot across the latter and terminating adjacent but not connected to the opposite wall of the slot, said part being resilient and having its free end normally disposed substantially in the same plane as said opposite wall but capable of being deflected out of said plane sufficiently to permit the eye of a key holder to be slipped upon it.

In testimony whereof I have affixed my signature.

WARNER R. BUXTON.
